CLAIM

The ornamental design for a boot for an in-line skate, as shown and described.

DESCRIPTION

FIG. 1 provides a perspective view of a boot for an in-line skate showing my new design;

FIG. 2 is a side elevation view of the skate of FIG. 1, with the broken line showing of a skate frame and wheels being provided for illustrative purposes only and forming no part of the claimed design;

FIG. 3 is an opposite side elevation view of the skate of FIG. 1; and,

FIGS. 4, 5, 6 and 7 are front, rear, top and bottom elevation views, respectively, of the skate of FIG. 1.
